UNITED STATES PATENT OFFICE.

FREEBORN F. RAYMOND, 2d, OF NEWTON, MASSACHUSETTS.

HEEL NAILING AND TRIMMING MACHINE.

SPECIFICATION forming part of Letters Patent No. 377,577, dated February 7, 1888.

Application filed November 10, 1887. Serial No. 254,746. (No model.)

To all whom it may concern:

Be it known that I, FREEBORN F. RAYMOND, 2d, of Newton, in the county of Middlesex and State of Massachusetts, a citizen of the United States, have invented a new and useful Improvement in Heel Nailing and Trimming Machines, of which the following is a full, clear, and exact description, reference being had to the accompanying drawings, forming a part of this specification, in explaining its nature.

The invention is an improvement upon that described in various patents heretofore granted me in my application for Letters Patent filed April 16, 1887, and in the application of C. C. Small, filed April 19, 1887; and it comprises an automatic heel nailing or attaching machine having a number of jacks adapted to be brought successively into operative position in relation to the heel-attaching devices.

It further relates to the combination of a series or number of jacks mounted upon a common support and adapted to be rotated or turned with said support into operative position with the heel-blank-attaching devices and said attaching devices.

It further relates to the organization, in an automatic heel-attaching machine, of a number or series of jacks mounted upon a common support and adapted to be rotated in relation to the heel-attaching devices, with said heel-attaching devices, comprising mechanism for automatically feeding the heel-blank and, when a top lift is separately fed, the top lift into position for attachment, an automatic nail-supplying mechanism, and a gang or group of awls and gang or group of drivers, with or without a heel-breasting device, also automatically brought into position and operated.

It further relates to a heel-nailing machine having a number or series of jacks each having a movable post, spindle, or support, said movable posts, spindles, or supports and a common head carrying the jacks and adapted to move the spindles or posts of the respective jacks into operative position with the attaching devices.

It further relates to the organization and combination, in a heel-attaching machine, of two or more jacks mounted upon a common support adapted to be moved to bring the

jacks into position, the heel-attaching devices, and heel-trimming mechanism.

It further relates to the combination, with heel-trimming devices, of a series of jacks mounted upon a common support and adapted to be moved to present heels in successive order to the heel-trimming mechanism.

It further relates to various features of organization and construction, all of which will hereinafter be explained.

In the drawings, Figure 1 is a view in front elevation of a machine containing the features of my invention. Fig. 2 is a view thereof in vertical section. Fig. 3 is a view in plan of the heel-trimming devices. Fig. 4 is a view in elevation of said devices. Fig. 5 is a view in horizontal section, taken immediately below the line of the templet-plate and in plan below said line, showing a heel-blank and top-lift feeding mechanism, which are not shown in Figs. 1 and 2, for the purpose of more clearly illustrating the invention.

Referring to the drawings, A is the frame of the machine.

A' is the templet, which preferably is stationary during the operation of the machine.

A'' is the nail-carrier, which is automatically moved into and out of position by the cam a upon the vertical shaft a', to carry nails from the automatic nail-supplying devices (not shown) to the templet.

B is a reciprocating head.

B' is a rotary head carried by the reciprocating head, and having the arm b supporting a block having a gang or group of awls, b', an arm, b'', having a block carrying a gang or group of drivers, b'', an arm, b'', and an arm, b'', carrying the heel-breasting knife b''. This head B' is rotated, preferably, by means described in said application of C. C. Small.

C is the heel-blank carrier, and C' is the top-lift carrier.

C'' is the stack of heel-blanks; C', a stack of top lifts; c, the heel-blank transerrer, and c' the top lift transferred. The heel-blank and top-lift transmitters are operated substantially as described in said Small application.

The jacks D are mounted upon the head or support D'. This head or support has horizontal guideways d for each jack, and it is also provided with a central hole, d', which re-

ceives the horizontal post or stud d^2 , with which the head D' is adapted to be turned. This post or stud d^2 is supported by and has bearings in the frame or bracket D' . (See Figs. 1 and 2.) Each jack D has a vertically-movable post, spindle, or support, d^3 , which supports the last or work-support d^4 , and each jack is adapted to be moved horizontally upon the head D' when it has been turned or moved to an upright position as represented in Fig. 1, with the last or jack-support beneath the templet A' and the spindle or post d^3 in line with the toggle-head E . The base of the jack in this event is supported by the head D' and by the table d^5 , which has ways d^6 in extensions or ways d of the head D' . The head D' and the table d^5 are not required to take any strain. They simply act to support the jack, the strain of the operation of the machine coming upon the toggle-head E and the templet A' . The head D' is locked automatically in position, to bring its guideway d in line with the guideway d^6 , by means of the spring registering-pin d^7 . (See Fig. 2.) The toggle-head E is made vertically movable by means of the cam e upon the vertical shaft a' , which has a cam-groove, e^2 . The lever e^3 is pivoted at e^4 , and has a cam-pin that enters the cam-groove e^2 , the toggle e^5 comprising the links $e^6 e^7$, the first of which is pivoted to the stationary support e^8 at its lower end, and the second of which is connected at its upper end with the slide-head e^9 , and the links of the toggle are connected with an arm of the lever e by means of the link e^{10} . The slide-head e^9 has a bearing in the bracket e^{11} , and the toggle-head E is vertically adjustable on the slide-head by screwing thereon. (See Fig. 2.)

This construction or organization of jacks and attaching devices allows a number of jacks to be moved successively into operative position and enables a saving in time to be effected, which is of very considerable importance in the operation of the machine, as it permits the operator to utilize the time which is otherwise of no account in removing the finished shoe from a jack moved out of position and the placing of an unheeled shoe upon a jack about to be moved into position; or, if an assistant be employed, it enables one to remove the work and the other to place it, and to thus increase the capacity of the machine very considerably.

I would say that it is not essential, so far as the material features of the invention are concerned, that each jack be movable horizontally upon the head D' , as the head itself may be placed in line with the templet and provided with a vertical movement.

The trimming apparatus G is represented as placed below the templet A and in a line therewith, and so that it may operate to trim or shave an attached heel simultaneously with the attaching of a heel to another boot or shoe by the heel-attaching devices above specified.

While I have shown the trimming mechanism as placed below the heel-attaching de-

vices, I would say that I do not confine myself to this location, as it may be placed upon one side thereof, in which event support for the jacks is organized to turn upon a horizontal plane. I prefer, however, when a jack rotating on a vertical plane is used to locate it between the jack and the nailing device, as indicated, as it makes a more compact construction, and because the skivings and chips from trimming are made below the principal working parts of the machine and cannot get into them, to interfere with their ready operation, and because it is more out of the way.

The trimming devices which I have represented are the well-known "McKay" devices described in various patents granted to Charles H. Glidden and used upon the heel-attaching machine known as the "McKay heel-attaching machine," and it is unnecessary to more than briefly say that they comprise a knife, G , which is carried by a block, g' , which is caused to be moved about the heel, and is guided in part by cam-tracks and in part by suitable forms or guides. The operative mechanism differs from the McKay in that the sprocket-wheel g^2 for rotating the knife-carrying block is revolved by means of a larger sprocket-wheel, g^3 , and by the chain G' , which connects the two sprocket-wheels. The sprocket-wheel g^3 is arranged upon a pivot or post, g^4 , and has a forward-and-back movement communicated to it by means of the cam g^5 upon the vertical shaft a' . This cam has a cam-groove, g^6 , which is connected with the sprocket-wheel g^3 by means of a lever, g^7 , which is pivoted at g^8 , and which is connected by a link, g^9 , with the cam-groove, and by the link g^{10} with the sprocket-wheel g^3 , and a partial rotation forward and back of this sprocket-wheel g^3 causes the knife-block to be rotated very nearly an entire revolution about the heel of the boot or shoe and to be returned to its original position.

There is attached to each jack, spindle, or post a boot or shoe holding and protecting device, H , which is movable therewith, and which is similar in construction to that described in the said patents and found in the said McKay machine. I would say, however, that, so far as the broad features of this invention are concerned, I do not confine myself to the special mechanism herein described for trimming the heel.

The sprocket-wheel g^2 and the cam and knife-block are supported upon a spindle, g^{11} , which has a bearing in the bracket g^{12} , (see Figs. 2 and 4,) and it extends below said bracket and its end rests upon the block g^{13} , which is carried in the front end of the lever g^{14} , and in relation to which it has a vertical movement in opposition to the spring g^{15} , the front end of the lever having a hole of sufficient size to receive the block g^{13} and spring g^{15} . The lever g^{14} is pivoted at g^{16} , and is operated by the cam g^{17} upon the shaft a' , having a cam-groove, g^{18} , and its office is to press or move the lower heel-trimming form, g^{19} , and

the knife-block upward vertically against or in relation to the heel of a boot or shoe upon the starting of the machine, and to maintain them in that position during the trimming of 5 the heel.

The front end of the lever g^{14} always has the same extent of movement, and for this reason I make the connection between it and the spindle g^{11} a yielding one, in order that the heel-form and knife-block may be always moved to any desired relation to the heel-blank, regardless of its height, the block g^{13} yielding with the spring g^{15} to allow this to take place.

The spindle g^{11} of course is made square, and 15 fits a square hole in the bracket g^{12} , to prevent its being turned.

In operation the operator preferably stands at the right side of the machine, the boot or shoe to be heeled and trimmed is mounted 20 upon the last or work-support, the first or second last or work-support to the right of the templet facing the machine. The last or work-support is then operated to move or bring the boot or shoe into position beneath the templet 25 A', and the machine is then set in operation. The jack-spindle of the last or work-support, which is in position, is then moved upward, compressing the heel-blank, which has previously been moved into operative position 30 beneath the templet, solidly against the same, the heel-blank is perforated, the attaching-nails fed and driven, the top lift fed, and the heel breasted automatically, as described in the Small machine. Meanwhile the operator 35 has been placing another boot or shoe upon the next last or work-support in order, and upon the completion of the attaching and breasting of the heel of the first boot or shoe the jack-support is turned to bring the second 40 boot or shoe into position, and the machine is operated as before.

If the trimming apparatus be not used, then the heeled boot or shoe may be removed from the last or work-support by a boy standing 45 upon the left of the templet; or the jack-support may be rotated and shoes presented in successive order to the nailing devices until the shoe first nailed reaches the operator, when he then removes the same and substitutes another, and continues to operate in 50 this manner.

When the trimming mechanism is employed, the heeled boots or shoes are advanced in successive order until they reach the trimming 55 mechanism, and after the first one in order has reached it the operation of the machine is as follows:

Upon the starting of the machine a heel is attached to one boot or shoe, while the trimming mechanism is caused to be automatically operated to simultaneously trim the heel previously attached to another boot or shoe. The rotation or movement of the jack-support having simultaneously moved into operative 65 position, one boot or shoe beneath the heel-attaching devices, and another boot or shoe into operative position in relation to the heel-

trimming devices, it is desirable that the heel should be under some degree of compression during the trimming operation, although, as a 70 rule, this should not be extensive, and in some cases it is not necessary or desirable that any more should be employed than to firmly hold the boot or shoe heel during the operation of the trimming devices.

I would say that I do not confine the invention to the employment of a jack-support movable upon a vertical plane, because it may be movable upon a horizontal plane, if desired; but I prefer the vertical plane, because it has some 80 advantages which the organization employing a jack-support movable upon a horizontal plane would not possess.

The advantages of the invention arise, first, from the rapidity with which the work may 85 be presented and removed from the heel-attaching device; second, from the saving in time which is obtained by the simultaneous attaching of one heel and the trimming of another by the same mechanism; and, third, by 90 the organization of the machine, which disassociates the heel-trimming mechanism from the nailing devices to such an extent that the construction is simplified and the parts of the heel-trimming devices made more accessible, 95 and the place of trimming removed from the place of nailing, so that the scraps, dust, and skivings cannot interfere with or check the nailing devices and the fine organization of the nailing mechanism permitted.

I would say in this connection that I am aware that it is not new to combine in one organization a heel nailing and trimming mechanism of a peculiar organization, which attaches what is known as a "loaded heel" and 100 then trims it as successive operations. I am not aware, however, that there has been any heel attaching and trimming machine organized which involves the automatic presentation of the heel-blank and top lift to attaching 110 devices and the use of attaching devices which involve the compression of the heel-blank upon the soles of the boot or shoe, the pricking of the holes therein after the heel-blank has been so compressed and the driving of the 115 attaching-nails; and I would further call attention to the fact that as the attaching of one heel and the trimming of another attached heel are simultaneous operations, a saving in time 120 is accomplished over the operation of a machine which first attaches loaded heel-blanks and top lifts and then trims the same heel.

Having thus fully described my invention, I claim and desire to secure by Letters Patent of the United States—

1. In a heel-attaching machine, the combination of the templet or pressure-plate, a movable head or support, and a number of jacks carried by said head or support, each of which has a sliding jack-post or spindle and a common pressure-applying head, E, as and for the purposes described.

2. The combination, in a heel-attaching machine, of a stationary pressure-plate or templet,

a movable pressure-applying head, and a series of jacks adapted to be moved by mechanism, substantially as specified, between the pressure-head and the templet or pressure-plate, as and for the purposes described.

3. The combination, in a heel-attaching machine, of a templet or pressure-plate, automatic heel-blank supplying and nail-driving devices, a pressure-applying head, and a number of jacks mounted upon a support movable by mechanism, substantially as specified, in relation to said pressure-applying head to bring the jacks between it and the templet, substantially as described.

15 4. In a heel-attaching machine having a templet or pressure-plate, an automatic heel-blank and top-lift-feeding device, or either of them, automatic nail-driving devices, a pressure-applying head, and a support or head movable by mechanism, substantially as specified, carrying a number of jacks and located or arranged in relation to the templet and the pressure-applying head to move or bring the jacks into operative position between the pressure-applying head and the templet, substantially as described.

30 5. The combination, in a heel-attaching machine, of the templet A', the last head or support D', having the guideways d, the jacks D, carried thereby, each of which has a movable jack post or support, d², and the pressure-applying head, substantially as described.

35 6. The combination, in a heel-attaching machine, of the templet A', the jack-supporting head or carrier D', having the guides d, a table, d⁵, having the guides d⁶, the jacks D, having the slide-last or work-support posts or spindles d⁷, and the pressure-applying head E, substantially as described.

40 7. The combination, in a heel-attaching machine, of the movable jack, head, or support D', having the guideways d, a series of jacks, D, carried thereby, and movable in said guideways, with the registering pin or lock d⁷, substantially as described.

45 8. The combination, in an organized machine for nailing and trimming heels, of a templet or pressure-plate, a heel-trimming apparatus, a jack support or head movable by mechanism substantially as specified, and two or more jacks carried thereby, the said jack support or head being arranged to carry or move the

jacks from operative position in relation to the templet or pressure-plate into operative position in relation to the heel-trimming apparatus, substantially as described. 55

9. In an organized machine for nailing and trimming heels, the combination, substantially as described, of a heel-attaching mechanism, a heel-trimming apparatus, two or more jacks, 60 and a movable support for the same adapted to transfer the jack or jacks from operative position in relation to the heel-nailing mechanism into operative position in relation to the heel-trimming apparatus, as and for the purposes specified. 65

10. In a heel-nailing machine, the combination of a heel-attaching mechanism, a heel-trimming apparatus, two or more jacks, a movable support for the same adapted to transfer the jacks from operative position in relation to the heel-nailing machine into operative position in relation to the heel-trimming apparatus, and a common prime motor for simultaneously operating the heel-nailing devices and the heel-trimming apparatus G, substantially as described. 70 75

11. The combination of a templet or pressure-plate A', the pressure-applying head E, the movable jack support or head D', the jacks 80 D, carried thereby, and the heel-trimming apparatus G, as and for the purposes described.

12. The combination of the movable last-head D', a series of jacks, D, carried thereby, the heel-trimming apparatus G, with which the 85 jacks are adapted to be brought successively into operative position, and a cam and lever for moving said heel-trimming apparatus into operative connection with each last or work-support, as and for the purposes described. 90

13. In an organized machine for nailing and trimming heels, in combination with an automatic heel-attaching and an automatic heel-trimming apparatus, a jack and a jack-carrier, and mechanism, substantially as specified, for 95 moving or transferring the jack from operative position with the heel-attaching apparatus into operative position with the heel-trimming apparatus, substantially as described.
